UNITED STATES PATENT OFFICE.

GEORGE E. KYSER, OF BIRMINGHAM, AND CHARLES E. THOMAS, OF CENTERVILLE, ALABAMA, ASSIGNEES, BY DIRECT AND MESNE ASSIGNMENTS, OF ONE-HALF TO SAID CHARLES E. THOMAS AND ONE-HALF TO J. A. THOMAS.

COMBINATION WOOD AND STEEL CROSSTIE.

Application filed August 14, 1919, Serial No. 317,557. Renewed August 28, 1922. Serial No. 584,765.

To all whom it may concern:

Be it known that we, GEORGE E. KYSER and CHARLES E. THOMAS, citizens of the United States of America, residing, respectively, at Birmingham, in the county of Jefferson, and Centerville, in the county of Bibb, and State of Alabama, have invented certain new and useful Improvements in Combination Wood and Steel Crossties, of which the following is a specification.

Our invention relates to a combination wood and steel railway cross tie which is characterized by the provision of effective means for mounting wooden filler blocks in position to carry the rails.

One object of our invention is to provide novel fastening plates adapted to engage the inner edges of the rail bases and the ends of the metal tie and to be held in operating position without the use of bolts or other fastenings, by the interposition between each adjacent pair of fastening plates of a wooden filler block.

It is a further important advantage of our invention that the metallic tie element is adapted to engage the outer rail flanges, thus positively preventing the rails spreading and giving a greatly increased safety factor to our ties. In this connection the wooden elements of the tie being relieved of the important duty of preventing the spreading of the rails can be used for their full life, i. e., as long as they will support the rail and hold the spikes.

Another important advantage of our invention lies in the fact that the wooden filler blocks can be replaced from time to time without disturbing the steel tie in its ballast bed and during the time the wooden blocks are out the steel tie will sufficiently support the rails to avoid the necessity of jacking them up.

A further object is to adapt the steel tie so that it will drain itself of water, thereby enabling the wooden filler blocks which it protects from contact with the ground to dry out quickly and thus give full life service.

These and other advantages of our invention will be better understood by reference to the accompanying drawings which illustrate only the preferred embodiment of our invention, and in which:—

Fig. 1 is a perspective view of our tie with the wooden filler block about to be in-

serted in position at one end of the steel tie and the rail shown in dotted lines resting on the other end of the steel tie showing the manner of its support when the wooden block is removed.

Fig. 2 is an enlarged plan view of one end of the cross tie with all parts assembled in operating position.

Similar reference numerals refer to similar parts throughout the drawings.

In the preferred embodiment of our invention illustrated in the drawings, we show a tie formed of metal and comprising a central body portion 1 which is flat unless it is desired to stiffen it in any suitable manner.

At each end this body portion 1 is provided with a pair of similar upturned integral side flanges 2 which are undercut along their top edges to form the rail seats 3 and undercut along their outer vertical edges to leave the overhanging lugs 4. These side flanges are

preferably vertically disposed and a fastening plate 5 is associated with each flange, the plate having its outer end bent outwardly at right angles to form a tongue 6 which will engage the end edge of the adjacent flange 2 and lock under its lug 4 and having its inner

end provided with an upturned overhanging rail engaging lug 7, which on its under face is sloped to conform to the sloping base of the rail 8. The plates associated with the flanges on one side of the tie have their tongues 6 bent in opposite directions from the plates associated with the flanges on the other side of the cross tie.

A wooden filler block 9 is adapted to be inserted in the channel at each end of the tie so as to make a close fit between and to secure the plates 5 in operating position and to form the primary support for the rail. These blocks are

preferably tapered at their ends and are about equal in length to the side flanges 2. They thus form wooden cushions or chairs under the rails and they receive the fastening spikes 10 which thus tie the rails to the blocks and by the interlock of the rail with

the plate lugs 7 on one side and the overhanging flanges 11 above the rail seat 3 on the other side, will thus serve to tie the whole fastening mechanism together.

In operation, a metallic steel cross tie is laid, the rails are dropped in position on the seats 3 and the tie plates are assembled and are interlocked with the flanges as shown in

Fig. 1. Thereafter the wooden filler blocks are driven into place and held there in position to support the rails with the spikes 10 driven thereinto and hold the plates 5 in position. When necessary to remove or replace a wooden block it is only necessary to draw the spikes, knock the block out and replace it with another block without disturbing the rail mounting or the position of the steel tie in its bed. The steel cross tie is self draining, protects the wooden filler blocks from the earth, and the blocks are exposed to the air in such manner that they will dry out rapidly, thus increasing their life and service. We prefer to confine the side flanges to the ends of the tie to reduce weight, but this feature is not of essential importance, it being only necessary that the metallic portion of the tie, whatever its intermediate construction may be, shall have side flanges at its ends to provide the rail supporting seats and the end flanges for the plates 5 to interlock with.

Our invention is not intended to be restricted in scope to the specific embodiments shown, but contemplates such modifications as come within the spirit and scope of the claims.

What we claim as new and desire to secure by Letters Patent, is:—

1. In a steel and wooden cross tie, a steel element formed of heavy sheet steel flat throughout its central portion and having upturned flanges at its ends, undercut rail seats in the top edges of said flanges, fastening plates adapted to engage the rail base and flanges so as to hold the rails on said

seats, and wooden filler blocks adapted to support the rails and to hold said fastening plates in operating position. 40

2. In a steel and wooden cross tie, a steel element formed of heavy sheet steel flat throughout its central portion and having upturned flanges at its ends, undercut rail seats in the top edges of said flanges adapted to prevent the outward displacement of the rails, fastening plates adapted to engage the rail base and flanges so as to hold the rails against inward displacement on said seats, and wooden filler blocks adapted to support the rails and to hold said fastening plates in operating position. 45 50

3. A cross tie comprising a metallic member having a flat bottom wall extending from end to end and side flanges upturned at each end, rail seats in said flanges having overhanging walls at the outer end thereof, a fastening plate disposed at each side of the tie with an overhanging rail engaging wall at the inner end of said seats and having an 60 out-turned lip to interlock with the outer ends of said flanges, and filler blocks adapted to be inserted between said fastening plates to hold them in operating position, the upper surface of the blocks being above the level 65 of the rail seats in said flanges and adapted to receive rail fastening spikes, substantially as described.

In testimony whereof we affix our signatures:

GEORGE E. KYSER.
CHAS. E. THOMAS.
